UNITED STATES PATENT OFFICE.

JACOB I. ROBIN, OF MOUNT VERNON, NEW YORK.

MANTLE-SUPPORT.

SPECIFICATION forming part of Letters Patent No. 696,493, dated April 1, 1902.

Application filed August 19, 1901. Serial No. 72,510. (No model.)

To all whom it may concern:

Be it known that I, JACOB I. ROBIN, a citizen of the United States, residing in Mount Vernon, Westchester county, and State of New 5 York, have invented certain new and useful Improvements in Mantle-Supports, of which the following is a specification.

My invention relates to supports for mantles employed in connection with incandescent gas-lamps. I will describe a support for a mantle embodying my invention and then point out the novel features thereof in a 10 claim.

In the accompanying drawings, Figure 1 is 15 a view in elevation of a mantle-support embodying my invention. Fig. 2 is a detail view in elevation. Fig. 3 is a detail perspective view.

Similar letters of reference designate corresponding parts in all of the figures.

A represents a burner-cap of the usual kind employed for incandescent gas-lamps. It is provided with the usual bayonet-slot *a* to permit of its being attached and detached from 20 the lamp.

A' represents a pair of brackets which are fixedly secured to the burner-cap A at diametrically opposite points thereof. Each bracket is provided with an upwardly-extending cylindrical portion *a'*, constituting a socket 25 to receive an end of one part of the support. The brackets A' may conveniently be made from a single piece of metal.

B represents the mantle-support, here 30 shown as comprising two vertical rods *b* and a cross rod or bar *b'* removably attached to the upper ends of the rods *b*.

Each vertical rod is bent at *b*² to have the portion *b*³ normally incline away from the 35 mantle C and with bends *b*⁴ and *b*⁵, the latter to form a shoulder or rest for the ends of the cross rod or bar *b'*. The cross rod or bar *b'* is provided with eyes *b*⁶ at its ends, through 40 which the ends of the vertical rods *b* project, and with a depending open loop or eye *b*⁷ to

receive the usual asbestos loop *c* of the mantle C.

It will be seen from Fig. 1 that when the complete support is in position on the burner-cap A the portions *b*² flare outwardly and cause the cross bar or rod *b'* to assume a horizontal position, and thereby hold the mantle properly over the burner-cap. The rods *b* are resilient and can be forced toward each other to permit of the removal of the cross rod or bar with its suspended mantle and another cross-rod carrying a mantle substituted. It is, however, preferable in practice that each burner-cap be provided with a complete support and mantle, which is to be substituted for the burner-cap and mantle which has been in use on a lamp. The burner-cap and support (complete as shown in Fig. 1) will be shipped in the usual container, and in this use the portions *b*² engage the cylindrical wall of the container to retain the device therein.

The ends of the rods are held in the cylindrical portions by means of the inwardly-extending tongues *a*² of the cylinder engaging in indentations in the rods.

It will be understood that the support, *per se*, may be separate from the burner-cap A and may be attached to any burner-cap provided with receiving-sockets.

What I claim as my invention is—

A mantle-support consisting of a pair of vertical rods, a support for one end of each rod, a bend provided in each rod just above its support to have an inclined part, bends at the upper end of each rod to form a rest and a cross rod or bar from which the mantle is supported, removably supported on the 75 rests of the vertical rods.

In testimony whereof I have signed my name to this specification in the presence of two subscribing witnesses.

JACOB I. ROBIN.
